UNITED STATES PATENT OFFICE.

ANTHONY B. FERDINAND, OF WAUWATOSA, WISCONSIN.

TIME DAMPER-REGULATOR.

No. 798,771.

Specification of Letters Patent.

Patented Sept. 5, 1905.

Application filed February 6, 1905. Serial No. 244,270.

To all whom it may concern:

Be it known that I, ANTHONY B. FERDINAND, a citizen of the United States, and a resident of Wauwatosa, in the county of Milwaukee, 5 and State of Wisconsin, have invented certain new and useful Improvements in Draft-Regulators; and I do hereby declare that the following is a full, clear, and exact description thereof.

10 My invention consists in certain peculiarities of construction and combination of parts hereinafter particularly set forth with reference to the accompanying drawings and subsequently claimed, one object of the invention being to provide for predetermined automatic closing of a check-door and simultaneous opening of a draft-door of a heating apparatus.

15 A further object of the invention is to provide for holding both of said doors more or less open at the same time.

Figure 1 of the drawings is a diagram illustrating connected check and draft doors of a heating apparatus and means in accordance 20 with my invention for controlling said doors; Fig. 2, a front elevation of the door-controlling mechanism, partly broken away and in section, on lines 2 2 in the next figure of the series; Fig. 3, a side elevation of said door-controlling mechanism, and Fig. 4 a horizontal section on the plane indicated by line 4 4 in Fig. 2.

Referring by letter to the drawings, A indicates a heater, and B its smoke-flue. A 25 flexible device C, such as a chain, is supported on suitably-arranged sheaves b and connects the lower draft-door D of the heater with a counterweight-bracket E, attached to the check-door F of the smoke-flue. The counterweight-bracket is connected by a chain G or other suitable device with a horizontal 30 handle-arm H of a slide I on a vertical rod J, the ends of this rod being extended through right-angle ears c of a back plate K, attachable to a wall or other suitable support and 35 constituting part of a frame, said ends of the rod being fast in collars d, opposing the plate-ears. A longitudinally-slotted front plate L of the frame is made fast to the ears c of the back plate, and one edge of the slot is angularly notched to form a rack for supporting the handle-arm H of the slide I at various 40 elevations, said arm being extended through said slot.

45 Loose on the rod J are offset horizontal ends of a vertical blade or rocker M, and op-

posing one side of the blade is a crank-arm N of the slide I aforesaid. The blade is also in the path of an offset lug e of the lower end of a crooked lever P, and said end of the lever 50 is in pivotal connection with the back plate K, the other end of said lever being thickened to form a weight f, that is normally caught by an offset portion g of a latch-plate Q, also in pivotal connection with said back 55 plate between stop-pins g', projecting from the same. A flange h of the latch-plate is arranged to overhang the alarm-winding key R, pertaining to a clock S, in detachable suspension from an upper forwardly-extended hook-arm T of the back plate. The clock shown is an ordinary alarm-clock; but the bell and clapper for the same may be omitted.

When the slide I is full down, the draft-door D is full open and the check-door F full closed; but the reverse is true if the handle-arm H of said slide is caught in the upper notch of the front plate-rack above specified, this being the position of said doors as herein shown. The lever P is normally caught by 70 the latch-plate Q in the position herein shown, and if the clock S in suspension from the hook-arm T of the back plate K be wound and set to have its alarm mechanism operate at a predetermined interval of time the reverse rotation of the winding-key R will cause a lift of said latch-plate to free said lever. Due to automatic swing of the freed lever the blade M is swung against the crank-arm N of the slide I and said slide is partially rotated to 75 bring its handle-arm H clear of the rack, in which it is held at a greater or less elevation above the bottom of the front-plate slot, the result being an automatic full closing of the check-door F and full opening of the draft-door D, the swing-blade M serving to prevent 80 said handle-arm of said slide from catching again in said rack when on descent.

It is principally intended that after fire in the heater is banked for the night the draft-regulator shall be set to full close the draft-door D and full open the check-door F, the clock being set and suspended, as described, to insure automatic release of the lever P at a predetermined hour in the morning, whereby 85 said fire may have opportunity to start up without personal attention.

The draft-regulator mechanism may be in an apartment above that in which the heating apparatus is established, and the adjustment 90 of the draft and check doors is variable at the will of the operator independent of the clock.

The clock is preferably detachable from the frame of the draft-regulator in order that said clock may be utilized elsewhere at will.

Having thus described my invention, what 5 I claim as new, and desire to secure by Letters Patent, is—

1. A draft-regulator comprising a frame attachable to a suitable support and provided with a rack edge slot, a rod in the frame, a 10 rocker loose on the rod, a slide on said rod provided with an arm engaging the aforesaid rack-slot and another arm opposing the rocker, draft and check doors of a heating apparatus, means connecting the doors with each other 15 and the slide, a rocker-actuating lever, and a clock-controlled latch engageable with the lever.

2. A draft-regulator comprising a frame attachable to a suitable support and provided 20 with an upper hook-arm and a rack edge slot, a rod in the frame, a rocker loose on the rod, a slide on said rod provided with an arm engaging the aforesaid rack-slot and another arm opposing the rocker, a rocker-actuating lever 25 a latch for the lever, a clock for which said hook-arm constitutes a hanger, a winding-key of the suspended clock being under the flange of the latch; draft and check doors of a heating apparatus, and means connecting the doors 30 with each other and said slide.

3. A draft-regulator comprising a frame attachable to a suitable support, a rod in the frame, a rocker loose on the rod, a slide adjustable on the rod to various elevations, means by which the slide is supported in adjusted position, an arm extending from said slide in opposition to the rocker, draft and check doors of a heating apparatus, means connecting the doors with each other and the aforesaid slide, a rocker-actuating lever, and 35 a clock-controlled latch engageable with the lever, release of said lever serving to automatically free the slide from adjusted position.

4. A draft-regulator comprising a frame attachable to a suitable support, a slide adjustable in the frame, means for holding the slide at various elevations, draft and check doors of a heating apparatus, means for connecting the doors with each other and the slide, and clock-controlled mechanism for the 40 release of the slide from any position of its adjustment.

In testimony that I claim the foregoing I have hereunto set my hand, at Milwaukee, in the county of Milwaukee and State of Wis- 55 consin, in the presence of two witnesses.

ANTHONY B. FERDINAND.
